UNITED STATES PATENT OFFICE.

THOMAS H. SEELY, OF MALDEN, MASSACHUSETTS, ASSIGNOR TO UNITED SHOE MACHINERY CORPORATION, OF PATERSON, NEW JERSEY, A CORPORATION OF NEW JERSEY.

WORK SUPPORT.

Application filed December 24, 1919. Serial No. 347,185.

This invention relates to work supports and more particularly to work supports for machines having operating instrumentalities for performing successive operations upon the work. In the illustrated embodiment of the invention herein shown the construction of the work support is well adapted for use with lasting machines of the hand method type, an example of which is disclosed in 5 United States Letters Patent No. 584,744, granted June 15, 1897, upon application of Ladd & McFeely. It is to be understood, however, that in its broader aspects and principles of operation the invention is of 10 general application.

An object of this invention is to provide a work support which, while giving the operator every facility for manipulating the work freely and presenting it in any desired relation 20 to the operating instrumentalities of the machine, will hold the work fixedly during the operation of those instrumentalities upon the work and relieve the operator completely from the exertion and consequent 25 fatigue of holding the work to the machine during such operation.

A feature of the invention consists in a work support organization including a work holder on which the work is held in predetermined position and which is freely movable to allow the operator, while holding the work or work holder in his hand, to present the work to the operating instrumentalities of the machine in the natural and usual manner to which he is trained, and a supporting structure which may be rendered fixed at times to hold the work while the said instrumentalities are performing an 30 operation or operations upon it.

When, as shown, the work holder is designed to hold a shoe and last, its movement preferably includes a rocking movement, that is, movement by which the shoe is positioned about a longitudinal axis; tipping movement, that is, movement by which the shoe is positioned about a transverse axis; rotative movement, that is, movement by which the shoe is positioned about an axis perpendicular to the shoe bottom; and translatory movement, that is, movement by which the shoe may be positioned by bodily movement vertically or horizontally.

The supporting structure, as shown, comprises triangle-forming rods connecting points on the last holder with points on a

rigidly supported base member. The rods are normally movable longitudinally through the last holder or base member, preferably the latter, and when held against movement in the base member form with the last 60 holder and base member a structure composed of triangles which is rigid against deformation in any direction on the well-known principle that a triangle is the only geometrical figure the shape of which cannot be changed without changing both the length of the sides and the angles. The simplest form of such a structure is an octahedron. Accordingly, in the construction shown, three points on the last holder, forming 70 the upper triangle, are connected to three points on the base member, forming the lower triangle, by three pairs of rods, each pair being arranged to connect one point of the last holder with two points of the base member, the six rods forming six side triangles which, with the upper and lower triangles, form an octahedral structure.

A further feature of the invention consists in means for maintaining the upper triangle in the same relation to the lower triangle, so far as relative rotation in a horizontal plane is concerned, and yet allowing rotation of both triangles together so that the last holder may have the rotative movement above mentioned. As shown herein, a base member, herein also termed a wheel member, is arranged for rotation substantially in a horizontal plane, and there are 80 connections between the last holder and the wheel member so arranged that rotation of one compels rotation of the other, the upper and lower triangles being so arranged that the corners of the upper triangle are over 85 the sides of the lower triangle.

A further feature of the invention consists in connections between the upper and lower triangles constructed and arranged to permit movement of the upper triangle toward and from the lower triangle, tipping or inclination of the upper triangle relatively to the lower triangle in any direction, and a bodily horizontal movement of the upper triangle relatively to the lower triangle in 105 any direction.

Another important feature of the invention consists in means for rendering the connections between the upper and lower triangles fixed or substantially rigid which, in 110

the construction shown, consists in means for locking the rods to the lower triangle or wheel member at their points of passage through it, the locking means being preferably operated in time relation to the operating instrumentalities of the machine in connection with which the work support is used.

Another feature of the invention consists in means for holding the support against rotation during the time it is held rigid against other movements. In the construction shown this is effected by locking the wheel member against rotation.

Another feature of the invention consists in a last holder comprising a heel pin and a forepart engaging member which are arranged for relative movement about a center located beneath the last to release the last, means for independently supporting the heel pin and forepart engaging member at times, and means for holding the center between the heel pin and the forepart engaging member from movement while said parts are independently supported to cause the last holder fixedly to hold the last.

Still another feature of the invention consists in a work support having three points of support whereby a structure rigid in all directions is provided. As shown, two points of support are on the machine head and the third is arranged for vertical movement so that the support is adjustable with the head when the head is moved up or down to suit the height of different operators.

These and other features of the invention including various novel constructions and combinations of parts will appear more fully from the following description when read in connection with the accompanying drawings and will be pointed out in the appended claims.

In the drawings,

Fig. 1 is a side elevation of a lasting machine provided with a work support embodying the present invention;

Fig. 2 is a view in front elevation of parts shown in Fig. 1;

Fig. 3 is a view in side elevation of the work support attached to a lasting machine;

Fig. 4 is a sectional plan view of parts shown in Fig. 8;

Fig. 5 is a sectional detail view on the line 5-5 of Fig. 6;

Fig. 6 is a sectional detail view, in elevation, on the line 6-6 of Fig. 8;

Fig. 7 is an illustrative diagram to be referred to; and

Fig. 8 is a sectional plan view taken on the line 6-6 of Fig. 3.

In the drawings, Fig. 1 represents, in side elevation, a work support or jack embodying the present invention applied to a machine having instrumentalities for operating upon a shoe held upon the support. The instru-

mentalities with which the illustrated machine is provided comprise a work rest 2 against which the bottom of the shoe is held, an edge rest 4 against which the side of the shoe is pressed, a gripper 6 which is operated to tension progressively successive portions of the upper, a wiper 8 which is reciprocated to wipe the tensioned upper against the bottom of the sole, and a driver 10 by which tacks are driven through the wiper 8 to secure the upper in lasted position.

The work support or jack includes a last holder which consists of a member 12 (Fig. 3) carrying a last pin 14 to engage the usual pin hole of the last and a forepart rest 16 which is pressed upwardly against the last to lift the forepart and cause the rear part to be cramped upon the pin 14 and held against vertical movement. The heel pin member 12 and the forepart member 16 are pivoted together at 18 by a pin extending transversely of the shoe. In the member 16 is a bore 20 containing a spring 22 the upper end of which rests against the bottom of the bore 20 and the lower end of which is enclosed in a sleeve-like plunger 24 having a bottom which rests on a projection 26 of the member 12. The effect of the spring 22, therefore, is to cause the member 16 to turn on the pivot 18 toward the shoe and to cramp and hold the shoe on the pin 14. The pivot pin 18, besides forming an axis for relative movement of the parts 12 and 16, has a bearing in a block 28 on which both the parts 12 and 16, which, taken together, are herein termed the "last holder", may turn together to effect a tipping movement of the last. The block 28 extends upwardly, as shown by dotted lines in Fig. 1, between bifurcations of the member 12 in a position to engage a face 25 on the member 16 when the last holder is tipped on the axis 18 more than is required in the normal operation of the machine. When this occurs movement of the member 16 is arrested while movement of the member 12 may be continued relatively to the member 16 to release the shoe from the holder and permit its removal. The block 28 is pivoted to ears on the head 30 by a pin 32 which constitutes an axis extending lengthwise of the shoe about which the last holder may be rocked laterally of the last. The head 30 is fixed to a tube or rod 34, a tube being preferred for the sake of lightness, which can turn on its longitudinal axis and, therefore, constitutes an axis at right angles to the axes of the pins 18 and 32, these three axes giving the last holder complete universality of movement substantially without translation.

It is necessary that the last holder have movements of translation both vertically and horizontally in all directions, not only to enable the shoe to be moved into and out of operative relation to the machine to en-

able it to be put on and taken off, but also to enable the varying horizontal and vertical contours of the shoe bottom to be presented at the same operative point to be acted upon by the operating instrumentalities of the machine. The capacity for universal movement possessed by the last holder combined with its capacity for movement of translation vertically and horizontally enables the operator, while holding the shoe in his hands in the usual manner, to present any desired part of the shoe to the operating instrumentalities in the position required for the most advantageous action of those instrumentalities. It is further desirable to provide means for holding the shoe against movement in response to the action of the operating instrumentalities, particularly the outward thrust of the wiper 8 and the downward impulse of the driver 10. In the construction to be described the last holder is locked against movement in any direction whatsoever.

The entire work support, including the last holder, as described, is carried by a frame 40 which is secured to the head 35 of the machine which has a neck 36 telescoping in the upper end of the column 42, the column being split and provided with a clamp screw 37 by which it may be clamped upon the neck 36. Straps 44, 46 (Fig. 8) are secured by screws 38 one to each side of the frame 40. The straps extend obliquely upward and are secured at their upper ends by screws 39 to the opposite ends of a yoke 48 which extends across behind the neck 36 to which it is securely clamped by a U-bolt 50. The screws 39 provide, therefore, two points of suspension for the frame 40. A third point of support is provided for the frame 40 by an arm 41 which, as shown, is integral with the frame and extends downwardly and around the column to the rear of the column where it has an ear 43 provided with a cylindrical hole that engages freely an enlargement 45 on a screw 49 by which the neck 36 is adjusted vertically in the column 42. The screw is threaded through a portion 51 of the column and has a conical end engaging a recess in the lower end of the neck 36. By loosening the clamp screws 37 and turning the screw 49 the neck 36 and head 35 may be adjusted vertically to suit operators of different heights. Incidentally, of course, the frame 40 and the work support mechanism will be carried up or down with the head and the operative relation of the work support with the operating instrumentalities of the machine will remain unchanged. The three-point support of the frame 40 provides a structure which is rigid in all directions and one which may be very readily attached to or removed from existing machines.

In the frame 40 is a circular rabbet 52

containing a split ring 54, the ends 56, 58 of which appear in Fig. 8. Fitting into the rabbet 52 above the ring 54 is a circular ring member 60 in which is one half of a ball race, the other half of which is formed in the periphery of a wheel-like base member 62. The ring 60 is secured to the frame 40 by screws 64 passing through lugs on the ring and threaded into the frame 40. Balls 63 are inserted into the ball race by removing a screw-plug 68 and constitute a ball bearing for the wheel or base member 62 to permit, normally, free rotation thereof when the last holder is turned, connection being established between the tube 34, which, as described, turns with the last holder, and the wheel member 62 to cause them to turn together. For this purpose the tube 34 carries between its ends two rolls 70 (Figs. 3 and 8) which are journaled on a pin 72 passing through the tube and through a short plug which fills the tube at this point and provides a suitable support for the pin 72. The rolls 70 move up and down with the rod, as the last holder is elevated and depressed, in a slot 74 formed in a hub member 76 and in a reduced upper portion 77 of the member, the rolls resting, when the last holder is in its lowest position, upon the bottom of the slot indicated in dotted lines at 78 in Figs. 3 and 6. The slot 74 steps short of the upper end of the portion 77 (Fig. 3) which is formed with an opening to guide the tube 34. The portion 77 is enclosed in a tube or casing 79 to exclude dust and dirt from the slotted portion and the rolls 70. When the last holder is raised to present the work to the machine the rolls 70 will occupy a position somewhere in the reduced upper portion or stem 77 of the hub member 76. The hub member 76 is spherical and is seated in the center of the wheel member 62, being retained therein by a cap ring 80 (Fig. 6) secured by screws 81. Thus the hub 76 has a universal joint connection with the wheel member 62 which permits the stem 77 of the hub to assume various inclined positions relatively to the member 62 as the last holder is moved in and out or sidewise. The hub 76 turns with the tube 34 when that is rotated axially by reason of the rolls 70 engaging the slot 74 in the stem 77 and the hub 76. To cause rotation of the wheel member 62 with the hub 76, a ball 82 is seated in a recess in the wheel member and engages a slot 84 formed in the hub 76. Thus, the stem 77 and hub 76, while able to tip in any direction by reason of their ball and socket joint with the wheel member, have any movement of axial rotation transmitted to the wheel member through the ball 82.

To sustain the last holder periodically in any position given it by the operator, an octahedral structure is provided. The mean

ing of the term "octahedral" as applied to this structure will be clear by comparing the geometrical figure of Fig. 7 with the structure to be described. In Fig. 7 a small upper triangle a, b, c is connected by six side triangles to a larger base triangle A, B, C. Obviously the position of the upper triangle a, b, c may be changed provided the sizes of at least three of the side triangles are changed. If the triangle a, b, c is moved bodily toward or from the base triangle A, B, C, the sizes of all of the six side triangles will be changed. The upper triangle a, b, c is represented in the structure herein shown by three points (Fig. 2), one point 90 being on the heel pin part 12 and the other two 92, 94 being on the part 16 which is extended laterally suitably to space these points apart. At these points respectively rods 91, 93, 95 are connected by ball joints. As close as is practicable to the ball joints other rods 96, 98, 100 are pivoted respectively to the rods 91, 93, 95. The six rods 91, 93, 95, 96, 98, 100 are arranged to form the six side triangles of the octahedral structure.

The wheel or base member 62 has three spokes 102, 104, 106, each of which is cylindrically bored longitudinally and contains between its ends means for locking two of the rods as closely as is practicable at a single point. Taking, for example, the rods 95 and 98, these rods pass through the spoke 102 (Figs. 6 and 8) which has slots 110, 112 above and below to permit their passage, these slots being at an oblique angle to the length of the spokes because of the slanting direction at which the rods enter them. In the cylindrical bore of the spoke 102 are two cylindrical members 114, 116 which can rotate in the bore and move longitudinally of it. Extending transversely of the cylindrical member 114 is a cylindrical locking member in two halves 118, 120. The rod 98 passes through a slot 122 in the member 114 parallel with its axis and wide enough freely to receive the rod and through grooves one in each half 118, 120 of the transverse locking member, the depth of the grooves being such that the halves 118, 120 can be pressed together to grip the rod before the flat sides of the halves come together. In the cylindrical member 116 is a transverse locking cylinder 124, 126 for the rod 95, the cylinder being constructed like the cylinder 118, 120. The adjacent halves 120, 124 of the two cylindrical locking members extend outside of the cylinders 114, 116 respectively and engage each other as is shown in Fig. 6. Obviously then, if the cylinder 114 is held against movement longitudinally of the spoke 102 and pressure is applied to the outer end of the cylinder 116, both locking cylinders 118, 120 and 124, 126 will be jammed against the rods 98, 95 respectively and will lock them against longitudinal movement.

Also when such pressure is not applied the rods will be free to move longitudinally and to assume any angle to the spoke 102 so far as permitted by the width of the slots 110, 112 (Fig. 5).

In the spoke 104 similar locking mechanism is provided for the rods 91 and 100 and in the spoke 106 similar locking means for the rods 93, 96. The inner cylindrical members of these locking mechanisms, corresponding to the member 114 of the mechanism in the spoke 102, are designated by the numerals 113, 115 and have on their inner ends protuberances 130, 131 which bear against the hub member 76. When the members 113, 115 are forced inwardly they first engage, by their protuberances 130, 131, the hub member 76 to lock that against movement in any direction and then offer the necessary resistance to cause the rod locking mechanism in the spokes 104, 106 to operate.

The cylindrical member 114 has a protuberance 133 which, instead of engaging the hub 76, engages a movable member 136 (Fig. 6) arranged to slide radially of the hub 76 and having an outer surface corresponding to the spherical curvature of the surface of the hub. The member 136 has a protuberance 138 which is arranged to engage the tube 34 and, upon inward pressure being applied to the member 136, to lock the tube 34 against longitudinal movement. To stiffen the tube against the lateral thrust of the protuberance 138, the portion of the tube below the rolls 70 may be provided with a septum 140 arranged with its edges in line with the direction of movement of the protuberance. Of course, a solid core could be provided for the tube but the thin septum furnishes the required rigidity with less weight to be moved by the operator.

To apply to each of the three cylindrical members 116 inward pressure to effect the locking of all the six rods and tube 34 against longitudinal movement, and the hub 76 and wheel member 62 against rotation, a single means is employed, namely, the split ring 54 before mentioned. In the outer end of each of the cylindrical members 116 is an adjustable screw stud 142 held in adjusted position by a set nut 144. The stud is so adjusted that its outer end will just clear the ring 54 when the ends of the ring are separated. To prevent excessive outward movement of the members 116 screws 146 are threaded into the spokes near their outer ends and have conical portions which enter V-shaped grooves in the members 116 (Fig. 4). The screws 146 are so adjusted and held by set nuts 148 that while limiting outward movement of the members 116 to prevent rubbing of the screws 142 against the ring 54, they will permit sufficient inward movement thereof to effect locking of the parts.

as described. Contraction of the ring 54 is effected by mechanism best shown in Figs. 3 and 8. The end 56 of the split ring 54 is held by an adjustable screw 150 which engages a suitable notch in the ring. A similar notch in the other end of the ring is engaged by a plunger 152 which is operated at the proper time by a lever 154 fulcrumed at 156 to the frame 40 and having a downwardly projecting portion 158 carrying a rounded stud 160 which engages the plunger 152. In the inner end of the lever 154 (Fig. 3) is a bore containing a plunger 162 having a stem 164 which extends through a hole in the bottom of a cap-sleeve 166 which is threaded into the bore of the lever. A spring 168 embraces the stem 164 and bears at one end against the plunger 162 and at the other on the cap-sleeve 166. The plunger 162 is cupped to receive a ball 171 on an operating rod 170, the ball being retained by a ball cap 172 threaded into the bore of the lever 154.

Obviously the construction described affords a yielding connection between the lever 154 and the operating rod 170 by which the thrust of the rod is transmitted to the lever 154 and thence to the locking plunger 152, and the tension of the spring 168 may be varied by turning the sleeve 166 to vary the force transmitted by the rod 170 to the plunger 152, movement of which will contract the ring 54 and lock the parts in the manner described. The rod 170 may be connected to any part of the machine, in connection with which the work support is used, which operates in the proper time relation to the operating instrumentalities to lock and unlock the work support at the required times or, of course, a special cam on the machine shaft may be provided for the purpose. As applied to the hand method lasting machine it is found that the rod 170 may be conveniently connected to the usual pleating lever 180 (Fig. 2) which operates in the required time relation to the other operating parts of the machine. As shown the rod 170 has a ball and socket connection at 182 with this lever 180. The end of the lever 180, to which the rod 170 is connected, is moved downwardly to effect locking of the work support before the wiper 8 operates upon the work and does not rise to release the work support until the driver has driven a tack. The shoe is, therefore, held, to the great relief of the operator, during those portions of each cycle in which stress is applied by the machine to the shoe, tending to move it from the position in which he has placed it and at other times in the cycle the shoe is left free so that the operator may move it freely at will and place it in the most advantageous position for the next operation of the machine.

It will be seen that the operator, in hold-

ing the shoe up to the machine, has to lift, in addition to the weight of the shoe, only the last holder, the six rods and the tube 34. These parts may all be made very light—so light in fact that the weight which the operator has to lift in addition to the weight of the shoe is insignificant compared to the great advantage gained by having the shoe securely held against displacement by the operating instrumentalities of the machine during their operation. The full locking pressure of the split ring 54 is applied simultaneously to all the locked parts, and since the locking is due to pressure on frictionally engaging surfaces, the pressure may be so adjusted that the parts, while held rigidly to withstand any normal stresses put upon them, will slip under undue or abnormal strains such as might be occasioned, for example by the accidental engagement of the positively operated wiper 8 with the side of the shoe instead of passing over the bottom of the shoe as it is intended to do. Thus undue strain upon the parts or breakage of them is avoided.

When no work is in the machine the rolls 70 will rest upon the bottom 78 of the slot 74 and the support may be swung outwardly as far as permitted by the engagement of the casing 79 in the extension 77 of the hub member against the retaining ring 80, as will be clear from Fig. 3. The portion 12 of the last holder may then be depressed, movement of the part 16 of the holder being limited by engagement of the face 25 with the block 28, the spring 22 being of course compressed. The last is then placed upon the pin 14, swung into position over the part 16, and the portion 12 released, whereupon the spring 22 will cause the part 16 to engage the forepart of the last and tip it to cramp the last upon the pin 14. The operator then takes the shoe in his hands in the same way that he is accustomed to do, raises it against the bottom of the rest 2, and places the portion of the side of the shoe at which he desires to be in the operation against the edge rest 4. He then steps upon the treadle to start the machine which, in the case of the lasting machine shown, will cause the gripper 6 to seize a portion of the upper and tension it upwardly and over the last, this action tending principally to lift the last against the support 2 without tending to displace the last. Before the wiper 8 begins to wipe the upper over the last, however, the lever 180 is operated to close the split ring 54 and lock the parts of the work support at the various points, as described, to hold the last holder firmly in position. The wiper then operates to wipe the upper into lasted position and the driver 10 operates to drive a tack through the wiper and into the last bottom. Immediately after the tack is driven the lever 180 re-

leases the split ring and the last holder is then perfectly free to allow the operator to present the work in a new position where the described operations will be repeated.

5 Having thus described my invention, what I claim as new and desire to secure by Letters Patent of the United States is:

1. In a machine of the class described, the combination of means for operating upon 10 various portions of the periphery of a shoe, shoe holding means constructed and arranged to allow movement of the shoe in all directions in presenting the shoe for the operation of the operating means, and means 15 for holding the shoe in the position in which it is placed by the operator during the operation of the operating means.

2. In a machine of the class described, the combination of means for operating upon 20 various portions of the periphery of a shoe, shoe holding means constructed and arranged to allow movement of the shoe in all directions in presenting the shoe for the operation of the operating means, and means 25 for holding the shoe against movement in any direction, said means acting in time relation to the operating means to hold the shoe immovably during each operation.

3. In a machine of the class described, the 30 combination of means for operating upon a shoe which tends to produce outward movement of the shoe, shoe positioning means to which the shoe is held in the hands of the operator, and supporting means for said 35 shoe constructed and arranged to hold the shoe against outward movement by the operating means during its operation and to permit free positioning movement of the shoe in all directions at other times.

40 4. In a machine of the class described, the combination of means for operating upon a shoe, a supporting base, a last holder arranged to permit free movement of the shoe and last holder relatively to said base in positioning the shoe for the operating means and being at such times unsupported by said base, connections between the base and the last holder, and means controlled by said operating means for rendering said connections fixed to hold the last holder during the 45 operation of the operating means.

5. In a machine of the class described, the combination of means for operating upon a shoe, a supporting base, a last holder 55 normally free for movement of the shoe and last holder in all directions relatively to said base in positioning the shoe for the operating means, the holder during such movement being unsupported except by the hands of the operator, connections between the base and the last holder, and means controlled by said operating means for rendering said connections rigid to hold the last holder against movement in any direction during the 60 operation of the operating means.

6. In a machine of the class described, the combination of means for operating upon a shoe which tends to produce downward and outward movement of the shoe, shoe positioning means to which the shoe is held in the hands of the operator, and supporting means for said shoe constructed and arranged to permit free vertical and in and out positioning movement of the shoe and to hold the shoe against any movement during 70 operation of the operating means.

7. In a machine of the class described, the combination of means for operating upon a shoe, a last holder, a base and connections therebetween constituting an octahedral structure normally capable of free change of shape, and means for rendering said structure rigid during operation of the machine upon the shoe.

8. In a machine of the class described, the combination of means for operating upon a shoe, a last holder, a base, rotatable means in said base and connections between the last holder and said rotatable means constituting an octahedral structure normally capable of 90 free change of shape, and means for rendering said structure and the rotatable means immovable during operation of the machine upon the shoe.

9. A work support for shoe machines comprising a rotatable last holder having a triangular bottom, a base having three points of support for the last holder and arranged for rotation with the last holder, three pairs of rods between the holder and the base, each pair connecting one point on the holder with two points on the base and arranged for movement through the point of connection with the base, and means for locking the rods against movement through the base and for holding the base against rotation.

10. In a shoe support or jack for shoe machines, the combination of a last holder having three points of support, a base having three points of connection to the last holder and connecting means between the points on the holder and the three points on the base constructed and arranged to permit free movement of the last holder in any direction, and means for rendering said connecting means immovable to hold the last holder in position.

11. A work support for shoe machines comprising a last holder having a triangular bottom, a base having three supporting points for the last holder, six rods connecting the corners of the last holder bottom to the three points of support whereby an octahedral structure is formed, the last holder being normally movable with resultant change of shape of the triangles formed by the rods, and means for holding said rods against movement to maintain the shape of said triangles unchanged.

12. A work support for shoe machines

comprising a last holder movable in all directions, and means to hold the last holder at times against vertical movement, rotative movement and tipping movement.

5 13. A work support for shoe machines comprising a last holder movable in all directions, and a single operating means to hold the shoe holder against movement in any direction.

10 14. A work support for shoe machines comprising a last holder movable in all directions, and means to hold the last holder at times against translatory movement in any direction.

15 15. A work support for shoe machines comprising a last holder movable in all directions, a base, connections between the last holder and the base normally permitting said movement of the holder, and means for rendering said connections rigid at times to prevent movement of the last holder in any direction.

20 16. In a machine of the class described, the combination of means for operating upon a shoe bottom, a rigid supporting base frame, rotary means supported in said base for movement in a horizontal plane, a last holder constructed and arranged to hold a last thereupon in predetermined position and movable to permit presentation of any portion of the shoe bottom to said operating means, connections between the last holder and the rotary means to cause said means to rotate with the last holder, other connections between the last holder and said rotary means, and means acting during operation of the operating means for rendering said other connections operative to hold the last holder against movement.

25 17. In a machine of the class described, the combination of means for operating upon a shoe bottom, a rigid supporting base frame, rotary means supported in said base for movement in a horizontal plane, a last holder constructed and arranged to hold a last thereupon in predetermined position and movable to permit presentation of any portion of the shoe bottom to said operating means, connections between the last holder and the rotary means to cause said means to rotate with the last holder, other connections between the last holder and said rotary means, and means for rendering all said connections effective to hold the last holder against movement while the shoe is operated on by said operating means.

30 18. In a machine of the class described, the combination of means for operating successively upon various portions of the periphery of a shoe progressively about the shoe, means for locating the shoe in predetermined position for such operations, shoe holding means constructed and arranged to allow movement of the shoe in all directions in presenting the shoe for the most advan-

tageous operation of the operating means upon each particular portion of the periphery, and means for holding the shoe in the position in which it is placed by the operator which means is effective only during the 70 operation of the operating means.

19. In a machine of the class described, the combination of means for operating successively upon various portions of the periphery of a shoe progressively about the 75 shoe, means for locating the shoe in predetermined position for such operations, shoe holding means constructed and arranged to allow movement of the shoe in all directions in presenting the shoe for the most advantageous operation of the operating means upon each particular portion of the periphery, and means for holding the shoe against movement in any direction; said means acting in time relation to the operating means 80 to hold the shoe immovably during each operation.

20. In a machine of the class described, the combination of operating instrumentalities to which any portion of the periphery 90 of a shoe bottom may be presented to be operated upon, a rigid base, a last holder which, while holding the shoe, securely permits presentation of the shoe held in the hands of the operator in any position best 95 adapted to receive the operation of said instrumentalities, connections between said base and said last holder constructed and arranged normally to allow free movement of the shoe for presentation of the shoe to 100 the machine in the desired position, and means for rendering said connections rigid during that portion of the machine's cycle when the operating instrumentalities tend to move the shoe. 105

21. In a machine of the class described, the combination of means for operating upon a shoe bottom, a rigid supporting base frame, rotary means supported in said base for movement in a horizontal plane, a last 110 holder constructed and arranged to hold a last thereupon in predetermined position and movable to permit presentation of any portion of the shoe bottom to said operating means, connections between the last holder 115 and the rotary means to cause said means to rotate with the last holder, a plurality of rods connecting points on the last holder with points on said rotary means, and means acting during operation of the operating 120 means for rendering said rods operative to hold the last holder against movement.

22. In a machine of the class described, the combination of means for operating upon a shoe bottom, a rigid supporting base 125 frame, means mounted in said base for rotation in a horizontal plane, a last holder constructed and arranged to hold a last thereupon in predetermined position and movable to permit presentation of any por- 130

tion of the shoe bottom to said operating means, connections between the last holder and the rotary means to cause said means to rotate with the last holder while permitting vertical translatory movement of the holder, rods connecting a plurality of points on the last holder with said rotary means, and means for rendering said connections and rods effective to hold the last holder against movement while the shoe is operated on by said operating means.

23. In a machine of the class described, the combination of operating instrumentalities to which any portion of the periphery of a shoe bottom may be presented to be operated upon, a last holder which, while holding the shoe and last securely upon it, permits presentation of the shoe while held in the hands of the operator in any position best adapted to receive the operation of said instrumentalities, a rigid base, connections comprising rods arranged in the form of triangles between said base and said last holder constructed and arranged normally to allow free movement of the shoe for presentation of the shoe to the machine in the desired position, and means for locking the rods to render the shoe rigid during that portion of the machine's cycle when the operating instrumentalities tend to move the shoe.

24. A work support for shoe machines comprising a last holder having a triangular bottom, a base having three points of support for the last holder, three pairs of rods having their upper ends connected two to each corner of the triangular last holder bottom and each pair diverging and passing through two of the three points of the support whereby an octahedral structure is formed, the last holder being normally movable with resultant change of shape of the triangles formed by the rods, and means for holding said rods against movement in the base to maintain the shape of said triangles unchanged.

25. A work support for shoe machines comprising a last holder having a triangular bottom, a base having three points of support for the last holder, three pairs of rods between the holder and the base, each pair connecting one point on the holder with two points on the base and arranged for movement through the point of connection with the base, and means for locking the rods against movement through the base.

26. In a shoe support or jack for shoe machines, the combination of a last holder having three points of support, a base having three points of connection to the last holder and connecting means between the points on the holder and the three points on the base constructed and arranged to permit free movement of the last holder in any direction, means for preventing relative ro-

tation between the last holder and the base, and means for rendering said connecting means immovable to hold the last holder in position.

27. In a device of the class described, the combination with a shoe support comprising a heel part rest having a last pin, a forepart rest pivoted to the heel part, and yielding means between the heel part rest and the forepart rest normally operative to cramp the last upon the last pin by raising the forepart, of means rigidly to sustain the heel part, means rigidly to sustain the forepart, and means to hold the pivot between the heel part and forepart against movement.

28. In a device of the class described, the combination with a shoe support comprising a heel part rest having a last pin, a forepart rest pivoted to the heel part, and yielding means between the heel part rest and the forepart rest normally operative to cramp the last upon the last pin by raising the forepart, of means acting periodically to hold the heel part, the forepart and the joint between them against movement rigidly to sustain the shoe.

29. In a machine of the class described, the combination of means for positioning a shoe vertically and horizontally, operating means which tends to produce movement away from said positioning means, a shoe holder in predetermined relation to which the shoe is held and which is movable laterally, vertically and rotatively to permit any portion of the periphery of the shoe to be held against the positioning means for the operation of the operating means upon various portions of the periphery successively, and means for holding the shoe holder against movement, laterally, vertically or rotatively during the action of the operating means.

30. In a device of the class described, the combination with a shoe support comprising a heel part rest having a last pin, a forepart rest pivoted to the heel part, and yielding means between the heel part rest and the forepart rest normally operative to cramp the last upon the last pin by raising the forepart, of means rigidly to sustain the heel part, means rigidly to sustain the forepart, and means to hold the pivot between the heel part and the forepart against upward movement relatively to the rigidly sustained parts.

31. In a device of the class described, the combination with a shoe support comprising a heel part rest having a last pin, a forepart rest pivoted to the heel part, and resilient means between the heel part rest and the forepart rest acting to cramp the last upon the last pin by raising the forepart, the shoe being releasable by compressing the resilient means, of means for holding the heel part, the forepart and the joint between them

against movement rigidly to sustain the shoe.

32. In a machine of the class described, the combination of means for positioning a shoe vertically and horizontally, operating means which tends to produce movement away from said positioning means, a shoe holder in predetermined relation to which the shoe is held and which is movable in all directions to permit any portion of the periphery of the shoe to be held against the positioning means for the operation of the operating means, and means for holding the shoe holder against movement in any direction during the action of the operating means.

33. In a machine of the class described having a supporting column and a head, the combination of a work support to sustain the work for the operation of the machine, and means rigid with the machine for sustaining the work support with which means the work support has only three points of contact.

34. In a machine of the class described having a supporting column and a head, the combination of a work support to sustain the work for the operation of the machine, and means rigid with the column and head for sustaining the work support and having three points of attachment to the support, said points being at the corners of a substantially vertical triangle.

35. In a machine of the class described having a supporting column and a head, the combination of a work support to sustain the work for the operation of the machine, and means for sustaining the work support having only two points of attachment to the head and only one point of attachment to the column.

36. In a machine of the class described having a supporting column and a head vertically adjustable with respect thereto, the combination of a work support to sustain the work for the operation of the machine, and means for sustaining the work support having two points of attachment to the head and one point of attachment to the column, said latter point being movable relatively to the column to permit vertical adjustment of the head.

37. In a machine of the class described, the combination of a rod, a halved cylinder embracing said rod, a larger cylinder having a seat extending at right angles to its axis for the halved cylinder, and means for applying pressure to the cylinders to lock the rod.

38. In a machine of the class described, the combination of a member having a seat for holding a plurality of cylinders for movement about their axes, a plurality of cylinders in said seat each having a cylindrical seat, halved members in said seats

arranged to contact one with another, a rod arranged between the halves of each of said members, and means for applying pressure to the cylinders in the direction of their axes to lock the rods against movement.

39. In a machine of the class described, the combination of a plurality of rods, a halved cylinder embracing each of said rods, larger cylinders each having a seat for one of the halved cylinders, said larger cylinders being constructed and arranged to permit rotation of the halved cylinders and to permit contact of one halved cylinder with another, and means for applying pressure endwise of the larger cylinders to lock the rods.

40. In a machine of the class described, the combination of a member having a seat for holding a plurality of cylinders for movement about their axes, a plurality of cylinders in said seat each having extending transversely of its axis a cylindrical seat, halved members in said seats arranged to contact one with another, rods arranged between the halves of said members, and means for applying pressure to the cylinders in the direction of their axes to lock the rods against endwise movement.

41. In a machine of the class described, the combination of a member having a spherical seat, a spherical hub member in said seat and having a groove, and a spline ball seated in said member and engaging said groove, the construction being such that rotation of the hub is imparted to the member and angular movement of the hub relatively to said member is permitted in all directions.

42. In a machine of the class described, the combination of a member having a spherical seat, a spherical hub member in said seat and having a groove, a spline ball seated in said member and engaging said groove, and means for locking the hub against movement in said member, the construction being such that when the hub and member are unlocked rotation of the hub is imparted to the member and angular movement of the hub relatively to said member is permitted in all directions.

43. A device of the class described having, in combination, a member carrying a last pin, a member having a toe rest, said members having a common pivot extending transversely of the shoe, and resilient means normally tending to move said members about their common pivot to cramp a shoe on the last pin.

44. A device of the class described having, in combination, a member carrying a last pin, a member having a toe rest, said members having a common pivot extending transversely of the shoe, resilient means normally tending to move said members about their common pivot to cramp a shoe on the last pin, a post having universal joint connection to one of said members, supplemental

means for separately supporting each of said members, and means for locking the post against longitudinal movement.

45. A device of the class described having, in combination, a member carrying a last pin, a member having a toe rest, said members having a common pivot extending transversely of the shoe, resilient means normally tending to move said members about their common pivot to cramp a shoe on the last pin, means for holding the common pivot against movement to release the shoe, and supporting means for said members operative only when the pivot is held from movement.

46. A device of the class described having, in combination, a vertically movable post, a heel pin member and a toe rest member pivoted to each other and to the post, means for locking the post against longitudinal movement, normally inoperative means for supporting said members, and means for causing said supporting means to become effective to support the members when the post is locked.

47. A device of the class described having, in combination, a heel part rest having a last pin to enter the thimble of a last, a fore part rest to engage the toe of a shoe on the last, means for relatively moving the toe and heel parts to cramp the last in position, an upright post having universal joint connection to the heel and toe parts, arranged for rotation about its longitudinal axis and for vertical movement, and means for locking the post against vertical movement.

48. In a machine of the class described, the combination of operating means, work holding means constructed and arranged to allow movement of the work in all directions to enable the work to be presented to the operating means, and means for locking the holding means in the position in which it has been placed by the operator during the operation of the operating means.

49. In a machine of the class described, the combination of operating means, work holding means, a support for said means constructed and arranged to allow the work holder to be moved into any position relatively to the operating means, and means operated in time relation to the operating means to render the support rigid against movement in any direction.

50. In a machine of the class described, the combination of operating means, a work holder, a base, connections between the work holder and base constituting a structure normally capable of free change of shape, and means for rendering said structure rigid during operation of the operating means upon the work.

51. In a machine of the class described, the combination of operating means, a work

holder, a base, rotatable means in said base and connections between the work holder and said rotating means constituting a structure normally capable of free change of shape, and means for rendering said structure and the rotatable means immovable during operation of the operating means upon the work.

52. In a machine of the class described, the combination of operating means, a work holder, a base, connections between the holder and base comprising rods in outwardly and downwardly inclined relation to the holder constructed and arranged to constitute a structure normally capable of free change of shape, and means for rendering said structure rigid during operation of the operating means upon the work.

53. In a machine of the class described, the combination of means for operating upon a shoe, a last holder, a supporting member, connections between the holder and the member comprising a deformable structure capable of free change of shape to permit movement of the holder in any direction, and means for holding the structure against deformation during operation of the operating means.

54. In a machine of the class described, the combination of a work holder, supporting means for the holder constructed and arranged to permit movement of the holder in every direction, and means for locking the work holder against movement in any direction.

55. A work support comprising a last holder, a supporting member, a deformable structure connecting the holder and the member and constructed and arranged to permit translatory movement of the holder in any direction independently of movement in any other direction, and means for holding the structure against deformation.

56. A work support comprising a last holding member, a base member, connecting means arranged to have substantial three-point bearings on both the last holder and the base member, said connecting means having pivotal connections to one of the members and being freely movable in the other member, and means for locking the connecting means from movement in said other member.

57. In a work support, a last holding member, a base member, rods connecting said members and movable bodily with respect to one of the members, and means for locking the rods to prevent relative movement of the members.

58. A work support comprising a work holder, a base, a plurality of rods connected to the holder and movable longitudinally in the base, and means for locking the rods.

59. In a work support, a shoe holder, a base member, a series of rods connected to

the holder and arranged to flare outwardly and downwardly therefrom and to have longitudinal movement through the base member, and means in the base member for locking the rods to the base member.

60. In a work support, a last holder, a base member, diverging rods connected to the holder and movable in the base member to permit movement of the holder in all directions, and means for locking the rods from movement in the base member.

61. In a work support, a last holder, a base member, diverging rods connected to the holder and longitudinally movable in the base member, and means for locking the rods against longitudinal movement.

62. In a work support, a shoe holder, a base member, connections between the holder and the base member arranged to flare outwardly and downwardly therefrom and movable relatively to the base member to permit movement of the holder in all directions while the center of gravity of the holder is maintained within the supporting area of the base member, and means for locking the connections to the base member.

63. In a work support, a shoe holder, a rotatable base member, a telescopic tube connecting the holder and base member and having universal joint connections to the base member, means for effecting rotation of the base member by rotation of the holder, and means for locking the universal joint against movement and for locking the base member against rotation.

64. A work support comprising a work holder, a base, a plurality of rods connected to the holder and movable longitudinally in the base, and locking means for the rods including a single member by operation of which all the rods may be locked.

65. A work support comprising a work holder, a base, a plurality of rods connected to the holder and movable bodily relatively to the base, and locking means for the rods including a split clamping ring by operation of which all the rods may be locked.

66. A work support comprising a last holder, a base, a triangular structure connecting the holder to the base, and means operable at times to permit and at other times to prevent deformation of said triangular structure.

67. In a machine of the class described, a

member having a cylindrical chamber with slotted walls, cylindrical members in the chamber, rods passing through the slots of the walls and the cylinders, and means for clamping the rods by application of endwise pressure upon the cylinders.

68. In a machine of the class described, a member having a cylindrical chamber with slotted walls, slotted cylindrical members in the chamber, rods in the slots of the member and cylinders, and clamping means engaging the rods and cylinders and each other operated by endwise pressure on the cylinders to clamp the rods.

69. In a machine of the class described, the combination of a member having a spherical seat, a stem having a ball seated in said seat, said ball having a groove extending in the plane of the axis of the stem, and means located in said groove for controlling relative rotation of the stem and member while movement of the stem is permitted as about axes at right angles to each other.

70. In a machine of the class described, the combination of a member having a spherical seat, a ball headed stem having its head located in said seat, said ball having a groove extending in the plane of the axis of the stem, and means comprising a ball located in said groove for controlling relative rotation of the stem and member while movement of the stem upon its head as a pivot is permitted.

71. In a machine of the class described, the combination of a member having a spherical seat, a ball headed stem having its head located in said seat, means for preventing relative rotation of the member and stem about the longitudinal axis of the stem while otherwise universal relative movement between the member and stem is permitted.

72. In a machine of the class described, the combination of a member having a cylindrical chamber, a cylindrical member mounted for rotation in said chamber and having a cylindrical bore extending transversely of its axis, half-cylindrical members in said bore, a rod passing between said half-cylindrical members, and means for applying pressure to clamp the said members upon the rod.

In testimony whereof I have signed my name to this specification.

THOMAS H. SEELY.
